INVENTOR:

UNITED STATES PATENT OFFICE.

WILLIAM L. LARGE, OF BROOKLYN, NEW YORK, ASSIGNOR TO THE OWEN CHINA CO.,
OF MINERVA, OHIO, A CORPORATION OF OHIO.

DESIGN FOR A PLATE OR SIMILAR ARTICLE.

46,173.

Specification for Design.

Patented July 28, 1914.

Application filed April 3, 1914. Serial No. 829,371. Term of patent 3½ years.

To all whom it may concern:

Be it known that I, WILLIAM L. LARGE, a citizen of the United States, residing at Brooklyn, in the county of Kings and State of New York, have invented a new, original, and ornamental Design for a Plate or Similar Article, of which the following is a specification, reference being had to the accompanying drawing, forming part thereof.

The figure is a plan view of a plate showing my design.

I claim:

The ornamental design for a plate or similar article as shown.

WILLIAM L. LARGE.
